UNITED STATES PATENT OFFICE.

ERVIN A. YOUNG, OF WADSWORTH, OHIO.

BOTTLE-NIPPLE PERFORATOR.

Application filed July 18, 1927. Serial No. 206,605.

The present invention is directed to improvements in devices for perforating nursing bottle nipples.

The primary object of the invention is to provide a device of this character so constructed that the size of the perforations in the nipples can be easily and accurately formed in order that the flow of milk or liquid foods, or compositions, can be regulated. It is a well known fact the consistency of liquid foods for infants varies and it often happens that the perforations of the nipples are of such size that the food feeds too fast or too slow, and it is to overcome this objection that the present invention has been perfected.

In the accompanying drawing:

Figure 1 is a side elevation of a device, showing the same supported upon a cup or bowl.

Figure 2 is a sectional view on line 2—2 of Figure 1.

Figure 3 is a view of a modified form of needle.

Figure 4 is another modified form of needle.

Referring to the drawing, I have illustrated the device as formed from a single length of suitable gage wire and comprising a tapered needle 1, which has its upper end terminating in a bar 2 which terminates in a vertically disposed shank 3, flattened and provided with sights 4 produced by forming notches in the outer face of the bar 3. The bar 3 has its lower end terminating in a resilient hook member 5 which is adapted to engage the side of a cup or bowl 6 in order to hold the device in its operative position.

The sights have stamped adjacent thereto numbers, the purpose of which will be later explained.

As shown in Figure 1, the nipple 7 is empaled upon the needle to the sight or notch corresponding with the number 3 of the shank. It is desirable that when the nipples are purchased that they will lack the perforations in order that when empaled upon the needle 1 the perforations will be of a diameter corresponding to the diameter of the needle at the point engaged with the crown of the nipple.

After the nipple has been empaled upon the needle at the desired sight or gradu-

tion, the needle is heated by a flame or if desired the needles may be electrically heated in any approved manner. When the needle 55 has become thoroughly heated it will melt or sear the nipple at the point of engagement with the needle, and as soon as the perforation is formed the weight of the nipple will cause the same to disengage therefrom leaving a perforation therein of the desired size. By providing the graduations or notches perforations may be made the desired sizes. To assure that the nipple crown will coincide with the desired sight or notch a person can 60 upon sighting along the line A regulate the distance the needle is to be engaged in the nipple.

In the modified form, as shown in Figure 3, the needle 8 is provided with a plurality 70 of circular heads 9, decreasing in size towards the point of the needle, it being obvious that the perforation in the nipple will be of a size corresponding to the size of the head which will engage under the crown of the nipple empaled thereon after the needle is heated, as herein before described. In the modified form, as illustrated in Figure 4, the needle 10 is provided with a plurality of cylindrical enlargements 11 varying in size, 80 and upon which the nipple is engaged, the size of the perforations being governed by the size of the enlargement. It will be of course understood that the needles 8 and 10 form a part of the bar 2 of the preferred form 85 of the invention.

It will be apparent that if it is not desired to support the device upon a cup or bowl, that the nipple may be held between the fingers and the device inverted, so that as soon as the needle becomes sufficiently hot the weight of the device will cause the same to disengage the nipple.

Having thus described the invention, I claim:

1. A device of the class described comprising a needle, a resilient hook carried by the needle for engagement with a support, and a shank disposed between the needle and hook and having graduations thereon, said needle adapted to be placed in penetrating engagement with a nipple at a point corresponding with a graduation.

2. A device of the class described including

a needle, said needle being adapted to penetrate a rubber nipple, means associated with the needle to regulate the penetrating engagement of the needle in the nipple, and 5 means for detachably mounting the device upon a support.

3. A method for perforating nursing bottle

nipples which consists in empaling the nipple upon the needle, then heating the needle, to melt the nipple at the point of engagement ¹⁰ with the needle, the heating of the needle releasing the nipple from the needle.

In testimony whereof I affix my signature.
